(57) **CLAIM**

The ornamental design for a baby bath, as shown and described.

DESCRIPTION

FIG. 1 is a perspective view of a baby bath, showing our new design;

FIG. 2 is a front view of the baby bath;

FIG. 3 is a rear view of the baby bath;

FIG. 4 is a left side view of the baby bath;

FIG. 5 is a right side view of the baby bath;

FIG. 6 is a top view of the baby bath; and,

FIG. 7 is a bottom view of the baby bath.

Any shading and cross-hatching are not features of the design but are utilized to illustrate the surface contours of the baby bath in the drawings.
